DRAWER LINING PAPER

Richard M. Carson, 4261 Briar Place, and Reuben R. Sacks, 1364 Cory Drive, both of Dayton, Ohio

Filed, Aug. 3, 1964, Ser. No. 81,137

Term of patent 14 years

(Cl. D59—2)

The figure is a plan view of a section of drawer lining paper showing our new design, the portions shown broken away being plain and unornamented.

We claim:

The ornamental design for a drawer lining paper, as shown and described.
